CLAIM

The ornamental design for a combined rocking seahorse safety ring and detachable toy figures, substantially as shown and described.

DESCRIPTION

FIG. 1 is a perspective view of a combined rocking seahorse safety ring and detachable toy figures showing my new design with two of the detachable toy figures in extended positions;

FIG. 2 is a perspective view of the side opposite that shown in FIG. 1 with two of the toy figures and the safety ring in extended positions;

FIG. 3 is a bottom plan view thereof;

FIG. 4 is a perspective view thereof with the toy figures in an attached position; and,

FIG. 5 is a perspective view of the side opposite that shown in FIG. 4.

FIG. 3

FIG. 5
